UNITED STATES PATENT OFFICE.

JENS HÖLTERMAND, OF AARHUS, DENMARK.

DEVICE FOR COUNTING ARTICLES OF DIFFERENT KINDS.

Application filed January 10, 1924, Serial No. 685,415, and in Czechoslovakia July 26, 1923.

This invention relates to a device for counting articles of different kinds, the device having a plurality of counting units which in a simple and reliable manner can 5 be put in action selectively to specify the number of each kind of articles.

This counting device may for instance be used in combination with or form a part of the cloth marking machine described in my 10 co-pending application Serial Number 592,890, in which case the counting device will serve to count the cloths marked by such machine according to groups (such as shirts, towels, sheets, etc.). The counting 15 device may, however, be used for other similar purposes.

In addition to the counting units corresponding to the various kinds of articles to be numbered respectively the counting device 20 may include a totalizing mechanism, i. e. a counter adapted to indicate the total sum of the figures set up by the said counting units at any time. The counting device also preferably is provided with a printing 25 mechanism by means of which one or more printed records of the items set up by the counting device may be taken.

On the drawing there is shown an embodiment of the invention which is able to 30 work as an entirely independent counting machine, but in which the frame of the device is particularly adapted to accommodate the working elements (perforator, knotter, etc.) of a marking machine of the type described in my said co-pending application, 35 these working elements themselves being, however, omitted as they form no part of the present invention.

Figure 1 is an elevation of the counting 40 machine, partially in vertical section along the line A—A in Figure 3.

Figure 2 is a vertical section along the line B—B in Figure 3.

Figure 3 is a top view of the machine.

Figures 4 and 5 are cross-sections of the 45 group counter and the totalizing mechanism respectively.

Figure 6 is a horizontal section of the group counter and the key-board for operating the same. 50

Figure 7 is a vertical section on a larger scale through part of the group counter.

Figures 8 and 9 are elevations of some of the counter operating members. 55

The frame of the machine.

The frame of the machine includes two vertical side plates P² and P³ which at their upper ends are connected to each other by means of a box-like frame P¹, while the lowermost ends of the side plates are rigidly interconnected by means of cross-beams P⁵ and P¹¹ and screw-bolts P¹². At the left hand side of the plates P² and P³, Figure 1, the space between these plates is covered by a screen P¹³, and the right hand side of the plates a similar screen P¹⁴ is arranged. The side plates are provided at their inner surface with reinforcing webs P¹⁰ in which the bearings for some of the shafts of the machine are formed. Extending outwards from the side plate P² is a horizontal frame R³, Figures 2 and 3, which is secured to the said side plate by the said screw bolts P¹² and a screw P¹⁷. The above mentioned frame members P², P³, P¹¹ and R³ bear 60 by means of a horizontal web P¹⁸ upon the uppermost edge of a casing R² and are secured to the same by screws R⁴, and this casing R² is by screws R⁵ secured to the base 65 frame R¹, which may be clamped upon any suitable foundation by anchoring bolts R⁶, 70 Figure 3.

In the space between the side plates P² and P³ is arranged a cam-sector O¹ adapted 75 to swing downwards from the position shown in full lines in Figure 1 to the position shown in dotted lines and back again. The downward swing of the cam sector is effected by operating a foot-pedal O¹² which 80 is pivoted on shaft O¹¹ and connected by means of a link rod O¹⁴ and pivots O¹³ and O¹⁵ to the cam-sector O¹. The foot-pedal 85 works in slots R⁷ in the base frame R¹ and 90

the casing R². The upward swing of the cam-sector is effected by a spring O¹⁶ connected by a pin O¹⁷ to the cam-sector and by a pin O¹⁸ to the side plate P². The upward and downward motions of the cam-sector are limited by stop bars O¹⁹ and O²⁰ respectively which are rigidly secured between the side plates.

This cam-sector O¹ is adapted to actuate the counting devices of the machine.

At the side of the plate P² facing away from the side plate P³ is mounted a counter casing Q¹, Figures 1-7, forming a vertical cylindrical chamber for receiving the numeral discs of the group counter and the totalizing mechanism. This counter casing Q¹ is provided with four lugs Q⁶ secured to the side plate P² by means of screws which are inserted through holes in this plate and screwed into threaded bores Q⁸, Figure 5 in said lugs Q⁶. The bottom opening of casing Q¹ is covered by the top wall of a frame member Q², which is U-shaped in cross-section and at the bottom thereof is provided with a bearing Q³ for a vertical shaft 34 to be further described in the following.

The group counter.

The essential elements and operation of the group counter will first be explained whereafter the detailed construction of the same is to be described.

A plurality of numeral rings 23 corresponding to the various kinds or groups of articles to be counted are placed on a vertical tube 24 mounted within the counter casing Q¹, Figures 2 and 4. The outer side of the rings are furnished with figures 26 from one upwards. The drawing shows twenty-eight figures, and the device shown can accordingly only number twenty-eight pieces of each group or kind of the specification. The inner side of the rings are furnished with teeth 25 the number and distances of which correspond to the figures 26 on the outer side, and a pawl 27, which is moved whenever the machine counts one piece, turns the ring by operating on the teeth of the inner side of the rings thus making another figure appear at 28 which is a long vertical slot in a plate 29, and the figures of the ring thus successively are brought into alignment with the front side of plate 29 which is a stereotype plate on which opposite each ring is a term for the kind of articles in the specification to be numbered by the ring in question. As is evident from Figures 2 and 4 the tube 24 has a long slot 30 through which the pawl 27 passes and engages with the rings. Between each pair of rings is a plate ring 31, engaging with the long slot in the tube 24 by a tongue 32. Consequently the plate ring cannot turn round on the tube, thus preventing the ring which is turned,

from moving the adjacent numeral ring. A space 33 is also created for the pawl 27 rendering the operating more secure and also preventing it from moving an adjacent ring. Pawl 27 may not only be swung to shift the numeral rings, but it is also selectively adjustable in a vertical direction so that it can be made to engage with any ring, and thus number any desired kind of the articles of a batch. The means for swinging and raising or lowering the pawl 27 will be described in the following. When all of the articles of an order have been numbered an ink ribbon is pressed against the plate 29 and the figures or types 26 of the numeral rings appearing in the slot 28. After a piece of a paper roll has been pressed against plate 29, and torn off it represents a detailed record of the articles numbered by the machine. When the contents of an order have been numbered the counting device must be replaced in its zero position. By turning tube 24 to the right round its axis on the plane of the drawing (Figure 4) the numeral rings on the tube will also be turned. On the outer side of each ring is furnished a projection 35. If a ring has not been moved during the counting or been moved but a small amount it will follow the tube on being turned, until the projection catches against the opposite edge of plate 29 when the tube will continue to turn without the ring. A stop is furnished on the tube to prevent it being turned more than till the projection 35 of a ring which has not been moved during the counting catches the opposite edge of plate 29. When the tube is turned so far round as permitted by the stop all the rings will be in the same position on the tube, and on turning the tube back to the position shown on the plan all the rings will follow and the counter be in its zero position.

The tube 24 is supported at its lower reduced end upon the stationary frame member Q², Figure 2, and is provided at its upper end with an end wall having a hollow hub N¹ which is guided in the top portion of the counter casing Q¹ and outside the latter is furnished with a crank N³ that is secured to the hub by a pin N² and provided with a handle N⁴, so that the tube 24 may be turned by hand. When the counter operates, the tube 24 should be locked in the position shown in Figures 2-7, and for this purpose crank N³ is provided with a spring 120 pressed pawl N⁵, Figure 2, which engages a depression formed in the upper side of the counter casing Q¹. The pawl N⁵ is provided with a head N⁶ by means of which the pawl may be lifted to thereby release crank N³ 125 and tube 24. The plate rings 31 arranged alternately with the numeral rings 23 are provided at their inner periphery with projections (not shown) which fit in circumferential grooves N⁷ formed in the outer surface 130

of tube 24. When the counter is assembled these projections on the rings 31 are inserted from below into longitudinal grooves N⁸, Figure 4, formed in the outer surface of 5 the tube, and the ring 31 is then lifted to the desired position and given a small turning movement whereby said projections on the inner periphery of the ring engage the desired circumferential groove N⁷, so that 10 the ring 31 is held in position on tube 24. It will be understood that each plate ring 31 thus carries the numeral ring 23 positioned immediately above the same. With 15 this arrangement each ring 23 can easily be turned independently of the other numeral rings by engagement with the selectively and axially adjustable pawl 27.

The totalizing mechanism.

20 The machine is also provided with an additional counter which counts the total sum of the figures presented by the rings 23 in slot 28. For this purpose the lowermost reduced end of tube 24, Figure 2, carries three 25 additional numeral rings N⁹ supported by plate rings N¹⁰. The construction and mounting of these rings N⁹ and N¹⁰ is quite 30 similar to that of the rings 23 and 31 respectively. Each numeral ring N⁹ is provided 35 at its outer periphery with thirty figures N¹¹ (three sets of digits from 0 to 9) Figure 5, and at its inner periphery with three recesses N¹² which may be engaged by a pawl N¹⁴. There are three such pawls N¹⁴, one for 40 each ring, and these pawls are pivoted independently of each other upon a stud N¹³ and serve to reset the rings N⁹ into the zero positions before the counter is to start a fresh 45 counting operation. The stud N¹³ is secured 50 to the frame member Q². The pawls N¹⁴ are 55 pressed yieldingly outwardly by means of springs N¹⁶ one end of which is secured in a stud N¹⁷ carried by the frame member Q², while the other end of the spring bears 60 against the rear side of the pawl as clearly 65 shown in Figure 5. Opposite to the pawls N¹⁴ there is produced an opening N¹⁸, in the tube 24 so that when the latter is turned 70 around its axis the pawls N¹⁴ will engage 75 those recesses N¹² which first appear in the opening N¹⁸, whereby the numeral rings N⁹ are carried to the zero positions, whereupon 80 the tube 24 is turned back again to its initial 85 position. Hereby pawl N¹⁴ and ring N⁹ will 90 be adjusted in the position shown in Figure 5.

To the upper surface of each ring N⁹ there is riveted a ratchet wheel N¹⁹ having 27 95 notches N²⁰ and three uniformly spaced 100 deeper notches N²¹ in order that a swinging 105 pawl N²² may turn the three rings N⁹ in the 110 well known manner so that the additional 115 counter formed by the rings N⁹ will be able 120 to count sums from 0 to 999. For this purpose 125 pawl N²² has a stepped engaging face 130

and normally only engages the numeral ring N⁹ of the lowermost order, while the notches N²¹ are provided for enabling the pawl to engage numeral rings of higher orders as is well known. Pawl N²² is mounted by means 70 of pivot N²⁴ upon an arm N²³ and pressed yieldingly towards the ratchet wheel by means of a spring N²⁶ one end of which is connected to the pawl and the other end to the pawl carrying arm N²³. The swing of 75 pawl N²² being greater than what corresponds to the ratchet wheel being advanced one tooth-space the counter casing Q¹ is provided with a stud N²⁸ which during part of the swing of the pawl prevents the same 80 from engaging the ratchet wheel N¹⁹ with the result that by each active swing of the pawl the ratchet wheel is only advanced one tooth-space.

The actuating means for the numeral discs. 85

The pawls 27 and N²² are operated from the cam sector O¹ at the last part of the downward swing of the same. The cam sector is provided with a projection O¹⁰, Figure 90 1, to which is pivotally connected a rod N³⁰ which is connected at its other end to a pivot N³² secured on a sleeve N³¹ which is arranged to slide vertically on the shaft 34. The pivot N³² is provided with a roller N³³, 95 engaging a slot N³⁴ in frame member Q². At the end of the downward stroke of cam sector O¹ and sleeve N³¹ the roller N³³ enters an inclined part of slot N³⁴, and hereby shaft 34 and the pawl carrying arms N³⁵ 100 (Figure 4) and N²³ (Figure 5) carried on said shaft will perform a turning movement, whereby the pawls 27 and N²² will advance the numeral rings 23 and N⁹ respectively.

The pawl carrying arm N²³, Figure 2, is 105 rigidly secured on shaft 34 and the pawl carrying arms N³⁵ and N²³ are connected to each other by means of a rod N³⁷ which is secured at its lowermost end in an arm N³⁸, 110 Figure 5, formed on pawl arm N²³. The rod N³⁷ further passes through a circular slot N³⁹ in the top portion of frame member Q² and slides freely through a hole formed in pawl arm N³⁵, Figure 4, whereas the 115 uppermost end of rod N³⁷ is secured to an arm N⁴⁰, Figure 2, which is rigidly secured on shaft 34. It is hereby obtained that arm N³⁵ carrying the pawl 27 is free to slide 120 vertically on shaft 34, while the arm is compelled to follow the angular movements of the shaft.

The pawl carrying arm N²³, Figure 2, and the sleeve N³¹ are connected to each other by means of a similar rod N⁴¹, the upper end of which is secured to a projection on the arm N²³, while the lowermost end of rod N⁴¹ is secured to an arm N⁴² rigidly secured on shaft 34. The rod N⁴¹ further passes freely through a hole in an arm N⁴⁴ projecting from sleeve N³¹. With 125 130

this construction sleeve N^{31} is free to slide vertically on shaft 34, while the latter is compelled to follow the turning movements of the sleeve. The upper end of shaft 34 is guided in a bore in hub N^1 , while the central part of the shaft and the lowermost end are guided in the frame member Q^2 . The shaft 34 is supported by means of the above mentioned arm N^{46} which bears against bearing Q^3 formed on the lowermost end of frame member Q^2 .

As above mentioned the pawl 27 is adjustable in vertical direction so that the pawl may be brought to engage any desired numeral ring 23. The vertical adjustment of pawl 27 is controlled by keys S^1 and actually effected by means of sleeve N^{31} , but since the latter always performs full strokes up and down means must be provided for releasing pawl 27 from sleeve N^{31} when the pawl reaches the desired numeral ring. The construction and operation of the keys S^1 with associated parts will be fully described in the following, but it is to be remarked here, that each key corresponds to separate kind of articles, and when a key is depressed and a carriage N^{64} is moved downwards at the downward stroke of cam-sector O^1 and sleeve N^{31} the motion of said carriage will stop when it reaches the depressed key, and then the carriage through certain operating members releases the driving connection between pawl 27 and sleeve N^{31} , so that the pawl is stopped in a position opposite to the numeral ring 23 corresponding to the depressed key.

The means for obtaining this result will now be described. The arm N^{35} carrying the pawl 27 is by means of a rod N^{53} Figures 2, 8 and 9 connected to a sleeve N^{47} loosely mounted on shaft 34 above sleeve N^{31} . The rod N^{53} is slideable in a longitudinal groove formed in shaft 34, Figures 4 and 6, and is provided at its upper end with a hook N^{54} , Figure 2, which engages the pawl carrying arm N^{35} while the rod N^{53} at its lowermost end is furnished with a hook N^{55} , Figures 8 and 9, which engages a horizontal slot in sleeve N^{47} so that the latter may remain unaffected by the turning movements of shaft 34, and on the other hand pawl carrying arm N^{35} and sleeve N^{47} will move vertically as a unit. The sleeves N^{47} and N^{31} may be connected together by means of a locking pawl N^{48} which is mounted on sleeve N^{31} upon a pivot N^{49} and provided at its upper end with a hook adapted to engage a projection N^{50} on sleeve N^{47} . This sleeve N^{47} is provided with an outwardly projecting arm carrying a detent N^{52} mounted on pivot screw N^{51} and adapted to maintain the locking pawl N^{48} in the position shown in Figure 8, in which sleeve N^{47} (and thereby also pawl 27) is compelled to follow the vertical motions of sleeve N^{31} . The detent N^{52} is by

means of a link N^{56} connected to a lever N^{57} swinging on a pivot N^{58} which is secured on the side plate P^2 . The lever N^{57} is by means of a link rod N^{62} connected to the above mentioned carriage N^{64} which is provided with a spring pressed push projection N^{67} . When the cam sector O^1 and sleeve N^{31} are moved downwardly, the pawl carrying arm N^{35} and the carriage N^{64} are also moved downwardly, and as soon as projection N^{67} on carriage N^{64} reaches a projection on the depressed key of the keyboard the swinging motion of lever N^{57} will cease, and since sleeve N^{31} continues its downward stroke the detent N^{52} will release locking pawl N^{48} , so that the movement of sleeve N^{47} is immediately stopped. Hereby the pawl carrying arm N^{35} , Figure 2, is also stopped and the pawl 27 is thus adjusted opposite to the numeral ring 23 corresponding to the depressed key S^1 , and since sleeve N^{31} is turned when it reaches the lowermost part of its path the shaft 34 will rock, whereby pawl 27 shifts the numeral ring 23 around tube 24. Simultaneously pawl N^{22} , Figure 5, will actuate the numeral ring (or numeral rings) N^9 so that the three numeral rings N^9 at any time indicate the total number of double-strokes of cam sector O^1 or in other words the sum of the figures presented by the various numeral rings 23 in slot 28, Figure 4. At the return stroke (upward stroke) of cam-sector O^1 the sleeve N^{31} , Figures 8 and 9, again engages sleeve N^{47} , and these sleeves are then locked together by means of locking pawl N^{48} which engages projection N^{50} , while detent N^{52} at the initial upward movement of sleeve N^{47} locks the locking pawl N^{48} . The sleeves N^{31} and N^{47} thereupon move jointly and carry pawl 27 and carriage N^{64} up to their normal positions as shown in Figure 2. The swinging movements of detent N^{52} is limited by means of inturned lips N^{68} provided on the same and arranged to engage opposite sides of the arm projecting from sleeve N^{47} . In Figures 8 and 9 the reference character N^{69} designates a spring pressed snap ball accommodated in a bore in said arm and adapted to engage one or the other of two depressions produced in detent N^{52} to thereby maintain the same in one or the other of its extreme positions. The movement of locking pawl N^{48} is limited by a pin N^{70} secured in sleeve N^{31} and engaging a slot in the locking pawl.

As above stated when the contents of an order have been counted the counter must be reset into the zero position before a fresh order can be dealt with. This is done by means of the handle N^4 , Figure 2. The snap pawl N^3 is released, and then tube 24 carrying the numeral rings 23 and N^9 is turned by means of crank N^3 in a counter-clockwise direction, Figure 2, until crank N^3 is

stopped by engaging a stop plate N⁷³ secured upon the counter casing Q¹. Hereby the projections 25 on the rings 23 will successively engage the stopping edge N⁷⁴, Figure 4, of the stereotypic plate 29, and simultaneously the three pawls N¹⁴, Figure 5, will engage those notches N¹² which appear in slot N¹⁸ and which through the rotation of tube 24 successively are moved to engagement with the pawls, whereby further turning movement of the numeral rings N⁹ is prevented. The crank N³ is then turned in the opposite direction to engage the opposite end of stop plate N⁷³. All of the rings 23 will then occupy the position shown in Figure 4, in which no figures are visible through slot 28, and the numeral rings N⁹ will indicate the figures 000 in slot 28. The counter is thus adjusted in the zero position, and a fresh counting operation may begin.

The locking devices for the tube carrying the numeral rings.

It will be understood from the foregoing that the crank N³ must not be turned in a clockwise direction before it has engaged stop plate N⁷³ at the end of the counter-clockwise turning movement. To prevent incidental turning of tube 24 the same is provided with a collar N⁷⁶, Figures 2 and 6, having teeth N⁷⁵ and two curved notches N⁷⁷. This collar is adapted to coact with a pawl N⁷⁸ pivotally mounted on stud N⁷⁹ secured on the counter casing Q¹ in the opening Q⁴. This pawl is normally held in the position shewn in full lines in Figure 6 by a spring N⁸⁰, one end of which engages the pawl while the other end is connected to a fixed hook N⁸². The notches N⁷⁷ are so positioned that when crank N³, Figure 3, engages one or the other side of stop plate N⁷³ one or the other of said notches will oppose the pawl N⁷⁸. When tube 24 is turned pawl N⁷⁸ will slip over the teeth N⁷⁵ and prevent incidental rotation of the tube in the opposite direction until a notch N⁷⁷ again opposes the pawl.

When the machine performs its functions the tube 24 is not only locked by the pawl N⁷⁸, Figure 2, but also by an L-shaped locking bar N⁸³, Figure 6, influenced by a compressed spring N⁸⁴ mounted between pin N⁸⁶ on bar N⁸³ and a shoulder formed on the inner side of the counter casing Q¹. One end of locking bar N⁸³ is adapted to engage an aperture N⁸⁵ formed in tube 24 to thereby lock this tube during the counting operation. When the machine has counted the articles of an order it is desired to produce a printed record specifying the numbers of the various kinds of articles as above mentioned, and to this end a strip of paper is pressed against the stereotypic plate 29 by means of a plate V¹, Figure 2, which thereby engages

the end N⁸⁷ of locking bar N⁸³, Figure 6, so that the locking bar is moved towards the right, and hereby the tube 24 is released. The locking bar is retained in the position shown in Figures 6 and 7 by a detent plate N⁸⁸ which is suspended by a riveted stud N⁸⁹ loosely engaging a wide bore in the wall of the counter casing Q¹, and provided outside this wall with a split N⁹⁰. To the detent plate N⁸⁸ is riveted a U-shaped member N⁹¹ which passes through the aperture Q⁴ in the counter casing and is connected by means of a spring N⁹² and a hooked pin N⁹³ to the fixed plate S² forming part of the keyboard. The spring N⁹² tends to draw the member N⁹¹ outwardly, and therefore as soon as the locking bar N⁸³ is moved towards the right as explained above the member N⁹¹ snaps behind the end of the locking bar as shown in Figure 6 and thereby maintains the same in the retracted position. When the tube 24 is afterwards turned to reset the numeral rings in the zero position the projection N⁹⁴ on tube 24 will slip over the projection N⁹⁵ on member N⁹¹ owing to the inclined engaging surfaces of these two projections. Hereby the locking bar N⁸³ is only pressed a little more towards the right but is not yet released from the detent plate N⁸⁸. However, when the tube 24 is turned back again, the projection N⁹⁴ will strike the projection N⁹⁵ so that the detent plate N⁸⁸ is pushed away from the end of the locking bar N⁸³, which therefore under the influence of spring N⁹² immediately engages the aperture N⁸⁵, thereby locking the tube 24 against rotation. The uppermost end of the tube 24 is provided with spare openings N⁹⁶, Figure 6.

The key board.

In order to make it possible to adjust the pawl 27, Figure 2, opposite to any desired numeral ring 23 there is arranged by side of the counter a key-board provided with as many keys S¹ as there are rings 23 in the group counter. This key-board comprises a plate S² the lowermost end of which is secured to the frame R², while the top end of the plate is secured to the counter casing Q¹. To the rear side of this plate S² is secured a rail S³, along which the carriage N⁶⁴ mentioned above travels. As shown in Figure 6 this rail S³ has a Z-shaped cross section. The carriage comprises a frame N⁶⁴, Figure 9, in which there are rotatably mounted four wheels N⁶⁶ upon shafts N⁶⁵. These wheels run on the rail S³ as shown in Figure 6. The carriage frame is provided with the above mentioned spring pressed push projection N⁶⁷. To the front side of plate S² there is secured by means of screws S⁶, Figure 2, a plate S⁷ which is furnished in alignment with each key S¹ with an inscription indicating a certain kind of articles and

being identical with that inscription on the stereotypic plate 29 which belongs to the numeral ring 23 corresponding to the considered key S^1 . The keys pass through a slot S^{10} in the plate S^2 , Figure 6, and are rotatably mounted on a common shaft S^8 , which is held in position upon the rear side of plate S^2 by means of a metal strip S^9 , Figure 2, which is provided with a longitudinal recess receiving the shaft S^8 , while the longitudinal edges of the strip are secured upon the rear side of plate S^2 . At each key S^1 the metal strip S^9 is provided with a slot so that the key may be mounted on the shaft and swing through said slot. The edge of rail S^9 facing upwards in Figure 6 presents a series of notches in alignment with the keys, so that when a key is depressed from the position shown in full lines to that shown in dotted lines the end of the key lying behind plate S^2 enters a notch and is maintained and supported therein, whereby it is obtained that the end of the key is not bent by the impact of projection N^6 on the carriage against the key.

To the rear side of plate S^2 there are secured four angle plates S^{11} , Figure 2, in which a bar S^{12} and a shaft S^{13} are secured. Each key S^1 is provided with a spring (not shown) which keeps the inner end of the key pressed against the rod S^{12} as shown in Figure 6. The shaft S^{13} carries a swing plate S^{14} influenced by a spring S^{15} , which tends to move the swing plate to the position shown in dotted lines, in which the plate bears against lugs S^{16} on the angle plates S^{11} and locks any depressed key S^1 by means of the edge S^{18} of the swing plate. The key is retained in this locked position until another key is depressed. The inner end of this second key will engage a projecting edge S^{17} on swing plate S^{14} and thereby push the edge S^{18} of the swing plate away from the key previously depressed, which, therefore, due to the action of its spring immediately swings towards its initial position adjacent the stop bar S^{12} , whereupon the key last depressed is locked by the swing plate. Thus it will be understood that in any moment only one key S^1 is retained in depressed position.

If during the operation of the machine the cam-sector O^1 is swung downwards and no key S^1 has been depressed, none of the numeral rings 23 of the counter will be turned, since the pawl 27 will be carried to a position below the lowermost ring 23, and simultaneously the pawl N^{22} by a simple mechanism (not shown) is prevented from turning the numeral rings N^9 . Thus the counter is put completely out of operation in the case of no key S^1 having been depressed.

To the swing plate S^{14} , Figures 2 and 6,

is secured an eye S^{19} which embraces a stud S^{20} on the lower end of a lever S^{21} which is mounted on a pivot S^{22} journaled in a lug Q^6 cast integrally with the counter casing Q^1 . The uppermost bifurcated end of lever S^{21} engages the locking bar N^{82} , so that when the latter is disengaged from tube 24 and moved to the position shown in Figure 6, the lever S^{21} will retract the swing plate S^{14} from the key depressed as the last one during the counting operation, whereby this key is released. When on the other hand the tube 24 is locked by the end of locking bar N^{83} engaging the aperture N^{85} , the stud S^{20} , Figure 2, on lever S^{21} will be so positioned that the swing plate S^{14} can move freely between the extreme positions shown in Figure 6, thereby locking and unlocking the depressed keys S^1 . Thus the swing plate is only put out of operation, when the locking bar N^{83} releases the tube 24.

The printing device.

When a number of articles has been counted, one or more printed records of the items set up by the counters is produced by means of a printing device arranged on the front side of the counting apparatus. This printing device comprises the pressing plate V^1 , Figures 2 and 3, to which side plates V^2 are secured by means of screws V^3 . The pressing plate V^1 is mounted to swing towards and away from the stereotypic plate 29 on a horizontal shaft V^5 which is secured in the side plates P^2 and P^3 and engages notches V^4 formed in the lower edges of the side plates V^2 secured on the pressing plate. The pressing plate V^1 is actuated by means of a crank V^6 , Figures 1-3, provided with a handle V and secured on a shaft V^7 journaled in bearings V^8 , Figures 1 and 3, which are carried by side plates V^9 . These side plates V^9 are clamped by means of screws V^{10} to the counter casing Q^1 . The said shaft V^7 carries between the side plates V^9 two eccentrics V^{11} which are connected to the pressing plate V^1 by means of plate links V^{12} , Figures 2 and 3, one end of which is provided with a boss V^{13} encircling the eccentric, while the inner ends of the plate links are rigidly interconnected by a bar V^{14} engaging notches V^{15} formed in lugs V^{16} on the pressing plate V^1 . Thus it will be understood that the pressing plate is swung on pivot V^5 when the shaft V^7 is turned by actuating the handle V . The bar V^{14} is maintained in the notches V^{15} by means of locking pawls V^{17} pivoted on screws V^{18} which are secured in the pressing plate V^1 .

When the machine performs its counting operations the crank V^6 occupies the position diametrically opposite to that shown in Figure 1, and then the pressing plate V^1

is retracted from the stereotypic plate, so that the numeral rings of the counter may be shifted freely.

Between the side plates V^2 , Figures 1-3, a paper feed roll V^{19} is mounted on a shaft V^{21} which fits loosely in holes in said plates and may be removed lengthwise by means of a handle V^{20} , Figure 3. The paper strip V^{26} , Figure 2, passes from the feed roll V^{19} downwards between two guiding rollers V^{24} and V^{27} , half round the circumference of the last named roller and then upwards between the stereotypic plate 29 and the pressing plate V^1 , the upper end of which is provided with a spring member V^{31} , Figures 1 and 2, adapted to hold the upper end of the paper strip, and further provided with a toothed plate V^{32} , against which the end of the paper strip when provided with a printed record may be torn off.

The above mentioned roller V^{24} has a rubber-coated cylindrical surface and is provided with two rigidly secured bearing pins, by means of which the roller is journalled in a bow V^{23} swinging on pivots V^{22} secured to the inner side of the plates V^2 . The roller V^{24} is pressed yieldingly against the roller V^{27} by means of a spring V^{28} connected at one end to a pin V^{29} on bow V^{23} at the other end to a pin V^{30} secured on side plate V^2 . The roller V^{27} is also provided with a rubber-coated cylindrical surface and is mounted on the side plates V^2 by two bearing studs. That bearing pin of the roller V^{24} which is nearest to the crank V^6 passes freely through a curved slot in the adjacent side plate V^2 and is provided outside the same with a head V^{25} , Figure 3, by means of which the feed roller V^{24} may be turned by hand to advance the paper strip.

As above mentioned the pressing plate V^1 is normally retracted from the stereotypic plate 29. When it is desired to produce a printed record the crank V^6 is rotated one complete revolution, whereby the pressing plate V^1 will press the paper strip V^{26} against the stereotypic plate 29 and also against the figures on the numeral rings 23 and N^9 appearing in slot 28, and then the pressing plate is moved back again. The desired record thus is printed on the paper strip by means of an ink ribbon X^1 which lies between the stereotypic plate and the paper strip. When the printed record has been made, the paper strip is drawn upwards, and the printed detailed record is torn off against the toothed plate V^{32} .

When the types of the printing device are to be cleansed the pressing plate V^1 is removed by swinging the locking pawls V^{17} upwards, whereby the bar V^{14} is released and may be swung upwards around shaft V^6 as pivot. The pressing plate V^1 with paper feed roll V^{19} and guiding rollers V^{24}

and V^{27} then is lifted out of engagement with shaft V^5 , drawn somewhat to the right and then removed by being drawn downwards in the space between the counter and the shaft V^1 .

The feeding device for the ink ribbon.

The ink ribbon X^1 lying between the stereotypic plate 29 and the paper strip V^{26} , Figure 2, has its ends wound on two bobbins X^2 and X^3 respectively, the lowermost of which X^2 is mounted to rotate on shaft V^5 , while the uppermost bobbin X^3 is rotatably mounted on a branch X^4 projecting from the stereotypic plate 29. This branch X^4 is provided with a horizontal guiding bar X^5 over which the ink ribbon X^1 is guided to the bobbin X^3 . The bobbins X^2 and X^3 are provided each with a ratchet wheel (not shown) which meshes with spring actuated pawls X^6 and X^7 respectively. These pawls are pivoted to horizontal arms on opposite ends of a vertical shaft X^8 which is mounted to turn and slide vertically in two bearings X^9 secured to the counter casing Q^1 . At any time only one of these pawls engages the corresponding ratchet wheel, and such engagement is maintained until the ink ribbon has been completely unwound from the other bobbin, whereafter shaft X^8 is displaced vertically to remove the pawl from the ratchet wheel and bring the pawl at the opposite end of the shaft in engagement with the other ratchet wheel. Thus it will be understood that the ink ribbon travels stepwise upwards between the stereotypic plate and then stepwise downwards and so on. The shaft X^8 is maintained in the uppermost and lowermost positions by means of a spring (not shown) which is placed in the uppermost bearing X^9 and adapted to engage one or the other of two spaced circumferential grooves in shaft X^8 . In Figure 2 the shaft X^8 is shown in its top position, in which pawl X^6 engages the ratchet wheel on bobbin X^3 .

When a printed record is taken and the pressing plate V^1 is thereafter moved to the right of the position shown in Figure 2, the pressing plate V^1 engages an arm (not shown) on shaft X^8 , whereby a small turning movement is imparted to this shaft, so that pawl X^6 will turn bobbin X^3 whereby the ink ribbon is drawn a short step upwards. This operation is repeated until the ink ribbon has been completely unwound from bobbin X^2 . When shaft X^8 is then turned again, the bobbin X^3 can not turn, and thereafter, pawl X^6 will swing to a vertical position around that end of the pawl which engages the ratchet wheel. Hereby shaft X^8 is displaced downwards to bring the other pawl X^7 in engagement with the ratchet wheel of bobbin X^2 . The pawl X^7 thereafter remains active, until the ink

ribbon has been completely unwound from bobbin X³, whereupon the direction of travelling of the ink ribbon is again reversed. When shaft X³ is displaced downwards from the position shown in Figure 2 the pawl X⁶ as indicated above will occupy a position in prolongation of the shaft. When the latter is turned next time a spring X¹⁰ will retract the pawl X⁶ to its normal position relative to shaft X³. Pawl X⁷ is provided with a similar spring.

Having thus fully described my invention I claim as new and desire to secure by Letters Patent:

1. A device for counting articles of different kinds or groups, comprising a plurality of mutually independent counting units corresponding to the different kinds or groups of articles to be counted respectively, a set of keys each of which correspond to one of said counting units only, an actuating member common to all of the said counting units and adapted to be selectively adjusted to operate any desired counting unit, and operating means serving to adjust the said actuating member in operative position relative to the counting unit corresponding to any depressed key and to cause the actuating member to shift such counting unit.

2. A device for counting articles of different kinds or groups, comprising a plurality of independently operable counting units corresponding to the different kinds or groups of articles to be counted respectively, a set of keys corresponding each to a separate counting unit, the counting units comprising each a numeral ring provided at its outer periphery with indicia and at its inner periphery with teeth corresponding to the indicia, a tube, all of said numeral rings being rotatable on said tube, and a swinging pawl operable through a slot in the said tube to engage the teeth of a ring to turn the same, said pawl being adjustable longitudinally of the axis of the tube to selectively engage any desired numeral ring in accordance with the operation of the keys.

3. A device for counting articles of different kinds, comprising a plurality of mutually independent counting units corresponding to the different kinds of articles to be counted respectively, a set of keys corresponding each to a separate counting unit, and means including an actuating member common to all of the said counting units for shifting any counting unit when the corresponding key is operated, said means comprising a carriage movable along the series of keys, driving means for moving the said actuating member through all its operating positions opposite to the various counting units and a releasable clutch interposed between said driving means and said actuating member and controlled by said carriage, so that when any key is operated and the driv-

ing means are made active the actuating member performs its movement and the carriage is allowed to move along the series of keys until it is stopped by the operated key, whereby the said clutch is released and the actuating member remains in a position opposite to the counting unit corresponding to the operated key.

4. A device for counting articles of different kinds, comprising a series of keys, a plurality of numeral rings constituting counting units corresponding each to a separate kind of the articles to be counted and to a separate key of said series of keys and provided each at its outer periphery with indicia and at its inner periphery with teeth corresponding to the indicia, a tube, all of said numeral rings being rotatable on said tube, a swinging pawl operable through a slot in the said tube to engage the teeth of a ring to turn the same, said pawl being adjustable longitudinally of the axis of the tube to selectively engage any desired numeral ring in accordance with the operation of the keys, a carriage movable along the series of keys, driving means for moving the said pawl through all its operating positions opposite to the various numeral rings and for moving the said carriage along the series of keys, a rotatable shaft arranged co-axially within said tube, and forming a guide for said longitudinally adjustable pawl which is non-rotatable on the shaft, a sleeve adapted to slide along said shaft and connected with said pawl, so as to move together with the same in the direction of the axis of the tube, a second sleeve non-rotatable on the said shaft but adapted to slide along the same and connected with the said driving means, a releasable clutch interposed between said sleeves and having releasing means controlled by the said carriage, and a guiding member having a slot, part of which is parallel to the axis of the tube while another part is inclined thereto, said second sleeve having a projection working in said slot, so that when the driving means operate to move the said pawl through its operating positions and to move the said carriage along the series of keys the carriage will be stopped by any depressed key, whereby the said clutch is released to leave the pawl in a position opposite to the numeral ring corresponding to the depressed key, while the said second sleeve continues its movement driven by the driving means and enters the inclined part of the slot at the end of its stroke, whereby this second sleeve as well as the shaft and the pawl are rocked to thereby shift the numeral ring.

5. The device of claim 4, with a totalizing mechanism adapted to indicate at any time the total sum of the figures presented by the various counting units, said totalizing mechanism including a set of coaxial totalizer

numeral rings rotatable on one end of said tube and operated by a single totalizer pawl secured on said rotatable shaft.

6. The device of claim 3, in which the keys are mounted to swing on pivots adjacent a plate having a series of notches, which are engaged by the keys when they are depressed to thereby support the keys against the impact of the said carriage.
- 10 7. The device of claim 3, in which the keys are mounted to swing on pivots adjacent a plate having a series of notches, which are

engaged by the keys when they are depressed to thereby support the keys against the impact of the said carriage, and in which a 15 spring actuated swing plate is adapted to lock any depressed key until another key is depressed, whereby the latter engages the swing plate and pushes the same away from the key previously depressed.

In testimony whereof I have affixed my signature.

JENS HÖLTERMAND.
